FIRE GRATE

Filed Dec. 9, 1946

INVENTOR.
Christian Lux
BY Marvin E. Elzinga

ATTORNEY.

UNITED STATES PATENT OFFICE

2,482,191

FIRE GRATE

Christian Lux, Sanish, N. Dak.

Application December 9, 1946, Serial No. 714,942

3 Claims. (Cl. 126—168)

1

This invention relates generally to fire grates and has particular reference to grates of this kind as used in vehicles or carriers, especially locomotives.

Carriers or vehicles of this kind are used in travel or movement which may tend to displace parts thereof and a particular object of this invention is the provision of means for keeping in proper place, and from jumping or undesirable relative movement of the grate structures of railroad locomotives.

Another object is the provision of an improved feature in fire grates which is capable of installation with the grates proper, which necessitates only minor changes in the grates for such installment, and which, though highly efficient, is still of a simplified nature.

A further object is to provide an improved attachment of this kind which is of a permanent nature, and which is so located as to be protected against being burned out.

A feature of the invention connected with the foregoing resides in a shaft, extension or arm of the grate; and shaft retaining means in the form of a rod or pin, with linkage including hook and shank means connecting said rod and the shaft.

A protection for said shaft, as aforesaid, is provided in part and in accordance with still another object of the invention, by dead ashes from the fuel consumed on the grate.

With the above indicated objects and advantages in view, as well as others which will hereinafter appear, the invention resides in certain novel constructions, elements and combinations of parts, the essential features of which are herein fully described and illustrated in the accompanying drawing, in which:

Fig. 1 is a plan view of an organization including a fuel grate constructed in accordance with this invention.

Fig. 2 is a side elevation thereof.

Fig. 3 is a section on the line 3—3 of Fig. 1.

Fig. 4 is a fragmentary plan view showing a modification of structure, and

Fig. 5 is a further modification of the structure shown in preceding figures.

In said drawing is shown a usual support or bridge structure 10, opposite sides of which are alike, the ends of bridge 10 being supported by the furnace structure, not shown. On one side of the support is a grate 11, and on the opposite side of said support is another grate 11. Each grate 11, with its associated parts and extensions is the same as the other, so that a description

of one is also applicable to the other, as identified by like reference characters.

A body portion 11 of a grate of this kind, having various types of openings therein, is well known to those skilled in the art, therefore this portion 11 is herein shown diagrammatically. The body 10 provides a seat for shaft 14 above a lower extension 12 which is formed with recess 13.

From the grate 11, of suitable material, extends a shaft 14, above the expansion 12, the other end of the grate 11 being supported by the furnace structure, not shown, so that this grate is maintained at proper level for use. With the recess 13, a recess 15, at right angles to the first recess communicates, and transverse to the recess 15 is a bore 16, extending through the support 10, the bore 16 therefore having opposite ends opening outwardly at the sides of said support.

20 Disposed in the bore 16 is a rod 17 and in each end of the rod 17 is a perforation to receive a cotter pin 20, the latter being outside of a disc or washer 21 thereat.

The rod 17 is therefore easily removable as 25 for taking apart any member of the structures, and for assembly. This rod 17 and the shaft 14 are connected by a link 22, having a ring end 23 on said shaft and a hooked end 24 on the rod 17. The material of the shaft 14, rod, and linkage 22 is the same as that of the grate 11.

In Fig. 4 is shown a shaft 14 having therein an annular groove 26 in which a ring end 123 of the link 22 is disposed, the end or ring 123 being therefore flush with or below the surface 35 of said shaft.

In Fig. 5 the shaft 14 is shortened and has a tapped hole to retain a screw 124, the same being equivalent to the reduced portion of shaft 14 in Fig. 4.

40 Variations may be resorted to within the scope of the invention and parts of the improvements may be used without others.

Having described my invention I claim as new:

1. In combination with a grate, a support with 45 a seat therein, a shaft extending from the grate to said seat, said support having therein a recess at right angles to the shaft, said support having also therein and in communication with the recess, a bore, a rod within said bore, and non-inflammable means connecting said shaft and said rod, said means disposed in said recess.

2. In combination with a grate bar, a support with a seat, a shaft extending from the bar to said seat, said support having therein a recess 55 at right angles to the shaft, the support having

also therein transverse to the recess and communicating with said recess a bore, a rod disposed in said bore, fire-proof linkage terminally engaging said shaft and said rod, the linkage having a shank in the recess, and holding means engaging said rod at opposite ends of said bore.

3. In combination with a pair of grate members and an interposed support having therein a pair of recesses providing seats, said support having a second pair of recesses at right angles to the first recesses and communicating with the first recesses, said support having extending therethrough and communicating with the second mentioned recesses through a bore, a rod passing through said bore, linkage disposed in said second recesses and having terminals engaging the respective shafts and terminals engaging said rod, said rod having perforations in

the outer ends thereof, and means cooperating with said perforations and holdingly engaging said ends of the rod.

CHRISTIAN LUX.
